UNITED STATES PATENT OFFICE.

JOHN W. HIGGINS, OF JACKSON, OHIO.

GAS-BURNER.

1,105,780.

Specification of Letters Patent.

Patented Aug. 4, 1914.

Application filed May 27, 1914. Serial No. 841,304.

To all whom it may concern:

Be it known that I, JOHN W. HIGGINS, a citizen of the United States, residing at Jackson, in the county of Jackson and State of Ohio, have invented a new and useful Gas-Burner, of which the following is a specification.

The present invention appertains to gas burners, and aims to provide a novel and improved gas burner applicable to the fire box of a furnace, boiler, stove, or the like.

The present invention contemplates the provision of a gas burner comprising a unique assemblage of component parts, to enhance the utility of the device, the present device including a peculiar arrangement of mixing tubes radiating from a central supply chamber, in combination with a hood or dome assembled with the mixing tubes in a novel manner to prevent back firing and to assist in supplying the air to the mixing tubes.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention has been illustrated in its preferred embodiment in the accompanying drawing, wherein:—

Figure 1 is a plan view, partly in section, of the burner, the section being taken on the line 1—1 of Fig. 2. Fig. 2 is a sectional view of the burner, taken on the line 2—2 of Fig. 1.

The present device embodies a central gas chamber 1, which is preferably in the form of a casting, and which has a lower inlet 2, into which the upper end of the gas supply pipe 3 is threaded or otherwise engaged. The periphery of the chamber 1 is provided with an annular series of outlet openings or apertures 4, in which are threaded outlet nipples or nozzles 5 which project radially from the chamber 1.

An annular series of radial mixing tubes 6 have their inner ends slipped over the outer ends of the nipples or nozzles 5, and are equipped at their outer ends with acute chambered burner heads 7. The mixing

tubes 6 are preferably integral with the heads 7, and the faces or outer sides of the heads 7 are provided with outlet apertures or orifices 8. The mixing tubes 6 project from the inner sides of the heads 7 intermediate the ends of the heads, and the heads 7, as a whole, are arranged in a circular or annular series.

The mixing tubes 6 are provided adjacent their inner ends, or adjacent the nipples 5, with air inlets 9, and air valves or shutters 10 are rotatably mounted upon the inner end portions of the mixing tubes 6 to control the passage of air through the openings 70 or air inlets 9.

A hood or dome 11 is disposed over the chamber 1, and is of a diameter sufficiently large, in order that the rim of the hood or dome may engage the mixing tubes 6 beyond the air inlets 9 and air valves or shutters 10. The rim or periphery of the bell or dome is provided with an annular series of downwardly opening slots or notches 12 which are engageable over the mixing tubes 6 beyond the air inlets 9.

In applying the burner within the fire box of a furnace, boiler, or the like, the chamber 1 is seated upon the grate, and the air supply pipe 3 is passed upwardly through the grate and attached to the chamber 1. The supply pipe 3 may be provided with a suitable controlling valve (not shown), to regulate the flow of gas into the chamber 1. The burner heads 7 may then be seated upon the grate, and the inner ends of the mixing tubes 6 slipped over the nozzles or nipples 5, in which event the hood or dome 11 may be placed over the chamber 1 and the inner end portions of the mixing tubes 6. The mixing tubes 6 being received by the slots 12 of the dome or hood 11, and the sleeveular or tubular air valves or shutters 10 being disposed within the dome or hood 11, will assist in holding the mixing tubes in engagement with the nipples 5, and furthermore, the hood or dome will inclose the air inlets 9 to prevent back firing.

In order that the hood 11 may assist in holding the mixing tubes in engagement with the nipples 5, it is essential that the valves or shutters 10 be frictionally or otherwise held against longitudinal movement relative to the mixing tubes, as will be obvious. The air is adapted to flow upwardly through the grate into the hood or dome 11 and from within the dome or hood 11, the air may enter the

air inlets 9 of the mixing tubes, to commingle with the streams of gas passing into the mixing tubes from the nipples 5. The central chamber 1 permits the gas to be readily supplied to the several nipples 5 and into the mixing tubes with approximate uniformity, and furthermore, the gas will be so agitated within the chamber 1, to assure of a proper discharge of the gas through the nipples or nozzles 5 into the mixing tubes wherein the air and gas will be admixed thoroughly. The mixture will then flow into the burner heads 7 from the mixing tubes 6, and will be discharged through the apertures 8 to support the flames. The flames will be arranged in an annular series to properly heat the sides of the fire box.

The several parts may be readily assembled and separated, and the present device is otherwise of advantage. The parts may be constructed in various sizes and proportions, so as to be applicable to various furnaces, boilers, stoves, and the like, and the number of mixing tubes 6 may be increased or diminished according to the circumstances.

Having thus described the invention, what is claimed as new is:—

1. In a gas burner, a chamber, radial mixing tubes having their inner ends slidably connected to the chamber to communicate with the interior thereof, a hood disposed

over the chamber and having its rim provided with downwardly opening slots engaged over the mixing tubes, the mixing tubes having air inlets within the hood, and members mounted upon the mixing tubes within the hood and with which the hood cooperates to assist in holding the mixing tubes in engagement with the chamber. 40

2. In a gas burner, a chamber having radial nipples, radial mixing tubes having their inner ends slipped over the said nipples, the mixing tubes having air inlets adjacent their inner ends and having burner heads at their outer ends, rotatable controlling valves mounted upon the inner end portions of the mixing tubes to control the passage of air through the air inlets, and a hood disposed over the said chamber, the rim of the hood having downwardly opening slots engaged over the mixing tubes, the hood inclosing the said air inlets and valves and coöperating with said valves to assist in holding the mixing tubes in engagement 45 with the nipples.

In testimony that I claim the foregoing as my own, I have hereto affixed my signature in the presence of two witnesses.

JOHN W. HIGGINS.
